UNITED STATES PATENT OFFICE

2,367,381

PICTURE ALBUM

Wladyslaw Szymlek, Techny, Ill.

Application June 15, 1942, Serial No. 447,041

4. Claims. (Cl. 40—28)

My invention relates to picture exhibiting, and more particularly to picture or post card albums, books or folders, especially of the type having hinged sections adapted to be folded and to unfold automatically by gravity when suspended from one end to exhibit all the different pictures or postcards on opposite sides of the sections merely by reversing the position of the top section, whereby the capacity of the device is substantially doubled as compared to known folders.

The object of the invention is to provide a picture album, omnibus book, magazine, or folder for holding a maximum plurality and relatively large number of pictures, photographs, snapshots or picture cards, such as post cards, in foldable relation, with or without a backing, cover or binding, so as to increase the picture or card carrying capacity of such devices not only substantially double compared to the capacity of ordinary albums or folders, but to facilitate exhibiting thereof, so that they may be viewed with greater convenience.

Another object of the invention is to arrange the pictures or cards, which may compose a set or series of views of related character, a particular place, locality or occasion, and which may depict various surroundings on one's sojourn and of personal or historic interest, or otherwise, in such a manner that the carriers or sheets are foldable, so as to be encompassed within a folder or cover if desired, and reversible or provided with pictures or picture cards on both sides, so as to practically double the number that can be accommodated in the cover, for a given length or strip thereof, and so that merely by the act of opening the cover and reversing the position of a carrying sheet or card and releasing the cards or pictures, they may be suspended in position to be viewed, and by a slight manipulation or reversing of the folded position of the cover or top picture and carrier, the remaining ones therebeneath will automatically and successively drop in cushioned fashion and progressive relation downwardly therefrom, so as to unfold singly or one at a time in downwardly progressive relation to be viewed, with but slight pull, strain or shock on the connections between the various or successive picture or card holding sheets, so that shocks will be absorbed and such strains or stresses will not break or destroy the connections, as compared to where they all drop at one time, such as with ordinary albums or folders of this type and in which the whole weight and stresses therefrom result in violent and excessive

strains on the connections or hinges between the cards or sheets, thus eliminating liability to breakage, severing, tearing or destruction of the connections.

5. Another object of the invention is to arrange the pictures or cards on sheets or flaps in two or more strips or plies foldable relatively in reversible positions in relation to each other and bearing the pictures, photographs or post cards on both or opposite sides, so as to be presented to view in reverse order or positions, which can be readily effected and controlled with but slight and simple manipulation of the top picture or cover, and held in either viewing position, as desired, while also making it possible to accommodate substantially twice as many pictures in a given length of strip comprising the folder, as compared with the ordinary folder. Ordinary card and picture folders or albums usually holding a plurality of cards or photographs, such as descriptive views or pictures of a series, are simply arranged by being held at the corners, clipped or pasted on opposite sides of a series of successively connected hinged cards or supporting sheets, or merely a strip foldable at various points, so as to overlie one another alternately in opposite directions in bellows-like fashion, so that six sheets or cards forming the backings of the pictures will hold only twelve photographs, pictures or post cards, but by my improved arrangement of album or folder, the same will hold twenty-two pictures or post cards with a strip of corresponding length, thus greatly increasing the holding capacity and facilitating the viewing thereof, as will be more fully described herein.
10. Another object of the invention is to provide a novel picture album or folder comprising wide and narrow strips, the wide strips having spaced sheets with narrow marginal connections in the form of strips or tapes, so as to accommodate the narrow strips and pictures or post cards mounted thereon between the marginal strips, so that they may lie against the alternate wide strips with the pictures thereon and alternately arranged in staggered relation, so that they may be reversed in position to exhibit opposite sides with accommodations for substantially twice as many pictures or post cards as ordinarily provided with known folders or albums. Also, by merely folding the top sheet or card holder together with the post card or picture thereon as a unit to reverse positions on opposite sides of the device, the remaining foldable picture carrying sheets alternately on opposite sides, therebeneath will be
15. Another object of the invention is to provide a picture album or folder comprising a top sheet or card holder, a bottom sheet or card holder, and a plurality of foldable picture carrying sheets, each having a top and a bottom, and being connected to the top sheet or card holder and the bottom sheet or card holder, so as to be suspended in position to be viewed, and by a slight manipulation or reversing of the folded position of the top sheet or card holder and the bottom sheet or card holder, the remaining ones therebeneath will automatically and successively drop in cushioned fashion and progressive relation downwardly therefrom, so as to unfold singly or one at a time in downwardly progressive relation to be viewed, with but slight pull, strain or shock on the connections between the various or successive picture or card holding sheets, so that shocks will be absorbed and such strains or stresses will not break or destroy the connections, as compared to where they all drop at one time, such as with ordinary albums or folders of this type and in which the whole weight and stresses therefrom result in violent and excessive
20. Another object of the invention is to provide a picture album or folder comprising a top sheet or card holder, a bottom sheet or card holder, and a plurality of foldable picture carrying sheets, each having a top and a bottom, and being connected to the top sheet or card holder and the bottom sheet or card holder, so as to be suspended in position to be viewed, and by a slight manipulation or reversing of the folded position of the top sheet or card holder and the bottom sheet or card holder, the remaining ones therebeneath will automatically and successively drop in cushioned fashion and progressive relation downwardly therefrom, so as to unfold singly or one at a time in downwardly progressive relation to be viewed, with but slight pull, strain or shock on the connections between the various or successive picture or card holding sheets, so that shocks will be absorbed and such strains or stresses will not break or destroy the connections, as compared to where they all drop at one time, such as with ordinary albums or folders of this type and in which the whole weight and stresses therefrom result in violent and excessive
25. Another object of the invention is to provide a picture album or folder comprising a top sheet or card holder, a bottom sheet or card holder, and a plurality of foldable picture carrying sheets, each having a top and a bottom, and being connected to the top sheet or card holder and the bottom sheet or card holder, so as to be suspended in position to be viewed, and by a slight manipulation or reversing of the folded position of the top sheet or card holder and the bottom sheet or card holder, the remaining ones therebeneath will automatically and successively drop in cushioned fashion and progressive relation downwardly therefrom, so as to unfold singly or one at a time in downwardly progressive relation to be viewed, with but slight pull, strain or shock on the connections between the various or successive picture or card holding sheets, so that shocks will be absorbed and such strains or stresses will not break or destroy the connections, as compared to where they all drop at one time, such as with ordinary albums or folders of this type and in which the whole weight and stresses therefrom result in violent and excessive
30. Another object of the invention is to provide a picture album or folder comprising a top sheet or card holder, a bottom sheet or card holder, and a plurality of foldable picture carrying sheets, each having a top and a bottom, and being connected to the top sheet or card holder and the bottom sheet or card holder, so as to be suspended in position to be viewed, and by a slight manipulation or reversing of the folded position of the top sheet or card holder and the bottom sheet or card holder, the remaining ones therebeneath will automatically and successively drop in cushioned fashion and progressive relation downwardly therefrom, so as to unfold singly or one at a time in downwardly progressive relation to be viewed, with but slight pull, strain or shock on the connections between the various or successive picture or card holding sheets, so that shocks will be absorbed and such strains or stresses will not break or destroy the connections, as compared to where they all drop at one time, such as with ordinary albums or folders of this type and in which the whole weight and stresses therefrom result in violent and excessive
35. Another object of the invention is to provide a picture album or folder comprising a top sheet or card holder, a bottom sheet or card holder, and a plurality of foldable picture carrying sheets, each having a top and a bottom, and being connected to the top sheet or card holder and the bottom sheet or card holder, so as to be suspended in position to be viewed, and by a slight manipulation or reversing of the folded position of the top sheet or card holder and the bottom sheet or card holder, the remaining ones therebeneath will automatically and successively drop in cushioned fashion and progressive relation downwardly therefrom, so as to unfold singly or one at a time in downwardly progressive relation to be viewed, with but slight pull, strain or shock on the connections between the various or successive picture or card holding sheets, so that shocks will be absorbed and such strains or stresses will not break or destroy the connections, as compared to where they all drop at one time, such as with ordinary albums or folders of this type and in which the whole weight and stresses therefrom result in violent and excessive
40. Another object of the invention is to provide a picture album or folder comprising a top sheet or card holder, a bottom sheet or card holder, and a plurality of foldable picture carrying sheets, each having a top and a bottom, and being connected to the top sheet or card holder and the bottom sheet or card holder, so as to be suspended in position to be viewed, and by a slight manipulation or reversing of the folded position of the top sheet or card holder and the bottom sheet or card holder, the remaining ones therebeneath will automatically and successively drop in cushioned fashion and progressive relation downwardly therefrom, so as to unfold singly or one at a time in downwardly progressive relation to be viewed, with but slight pull, strain or shock on the connections between the various or successive picture or card holding sheets, so that shocks will be absorbed and such strains or stresses will not break or destroy the connections, as compared to where they all drop at one time, such as with ordinary albums or folders of this type and in which the whole weight and stresses therefrom result in violent and excessive
45. Another object of the invention is to provide a picture album or folder comprising a top sheet or card holder, a bottom sheet or card holder, and a plurality of foldable picture carrying sheets, each having a top and a bottom, and being connected to the top sheet or card holder and the bottom sheet or card holder, so as to be suspended in position to be viewed, and by a slight manipulation or reversing of the folded position of the top sheet or card holder and the bottom sheet or card holder, the remaining ones therebeneath will automatically and successively drop in cushioned fashion and progressive relation downwardly therefrom, so as to unfold singly or one at a time in downwardly progressive relation to be viewed, with but slight pull, strain or shock on the connections between the various or successive picture or card holding sheets, so that shocks will be absorbed and such strains or stresses will not break or destroy the connections, as compared to where they all drop at one time, such as with ordinary albums or folders of this type and in which the whole weight and stresses therefrom result in violent and excessive
50. Another object of the invention is to provide a picture album or folder comprising a top sheet or card holder, a bottom sheet or card holder, and a plurality of foldable picture carrying sheets, each having a top and a bottom, and being connected to the top sheet or card holder and the bottom sheet or card holder, so as to be suspended in position to be viewed, and by a slight manipulation or reversing of the folded position of the top sheet or card holder and the bottom sheet or card holder, the remaining ones therebeneath will automatically and successively drop in cushioned fashion and progressive relation downwardly therefrom, so as to unfold singly or one at a time in downwardly progressive relation to be viewed, with but slight pull, strain or shock on the connections between the various or successive picture or card holding sheets, so that shocks will be absorbed and such strains or stresses will not break or destroy the connections, as compared to where they all drop at one time, such as with ordinary albums or folders of this type and in which the whole weight and stresses therefrom result in violent and excessive
55. Another object of the invention is to provide a picture album or folder comprising a top sheet or card holder, a bottom sheet or card holder, and a plurality of foldable picture carrying sheets, each having a top and a bottom, and being connected to the top sheet or card holder and the bottom sheet or card holder, so as to be suspended in position to be viewed, and by a slight manipulation or reversing of the folded position of the top sheet or card holder and the bottom sheet or card holder, the remaining ones therebeneath will automatically and successively drop in cushioned fashion and progressive relation downwardly therefrom, so as to unfold singly or one at a time in downwardly progressive relation to be viewed, with but slight pull, strain or shock on the connections between the various or successive picture or card holding sheets, so that shocks will be absorbed and such strains or stresses will not break or destroy the connections, as compared to where they all drop at one time, such as with ordinary albums or folders of this type and in which the whole weight and stresses therefrom result in violent and excessive

caused to drop in reverse positions, so that the pictures on opposite sides can all be exhibited or viewed, but will be covered and unexposed in one position and uncovered and exposed in another position without requiring individual grasping and independent swinging and folding of the various pictures or post cards in order to present the same to view.

Still another object of the invention is to provide a photograph, picture or post card album of the foldable type which can be produced from two strips of single or double ply material fastened together at one end of each strip and having a plurality of picture carrying sheets foldable one on another in a novel manner and so arranged that by reversing the position of the top carrying sheet or a cover provided thereon, the album will unfold in opposite directions to expose opposite sides or faces of the carrying sheets to exhibit and expose to view the photographs or pictures thereon. Also, the strips may be continuous or independent single or double ply cards or sheets hinged together in foldable relation by independent tapes, so that a comparatively inexpensive or a more expensive and high-class product may be produced so as to come within the range of purchase of everyone, and in either instance produce a device which can be economically manufactured in large numbers and assembled with facility but which will be strong, substantial and not likely to get out of working order.

Further objects and advantages will appear and be brought out more fully in the following specification, reference being had to the accompanying drawings in which:

Fig. 1 is an elevation of a wide strip or blank constituting a part of one form of picture album or folder in accordance with the invention and showing the relation of a narrow strip fastened thereto in dotted lines at the bottom.

Fig. 2 is a view similar to Fig. 1 of a narrow strip or blank forming the other part of the album or folder and showing the relation of the wide strip thereto in dotted lines at the top.

Fig. 3 is a fragmentary perspective view showing the connected ends of the wide and narrow strips with a modified form of fastening means.

Fig. 4 is a perspective view showing a picture album or folder made with the parts shown in Figs. 1 and 2 and showing the manner of assembling same with certain parts opened out in the act of folding and fastening the same together.

Fig. 5 is a fragmentary perspective view showing the manner in which the device unfolds.

Fig. 6 is an elevation of the device in unfolded suspended position.

Fig. 7 is an elevation of another form of the invention opened out in suspended position.

Fig. 8 is a view similar to Fig. 7 but looking at the opposite side with the device in a reverse position.

Fig. 9 is a fragmentary perspective view showing the manner of reversing the device from the position shown in Fig. 7 to the position shown in Fig. 8.

Figs. 10, 11 and 12 are enlarged cross-sections taken on the lines 10-10, 11-11 and 12-12 of Fig. 8.

Fig. 13 is a view similar to Fig. 7 showing a slightly different mounting.

Fig. 14 is a diagrammatic sectional view taken on the line 14-14 of Fig. 13.

Fig. 15 is a view similar to Fig. 14 but showing the parts in reverse position.

Fig. 16 is an enlarged cross-section taken on the line 16-16 of Fig. 13, and

Fig. 17 is an enlarged longitudinal section through three of the foldable sections or hinged picture carrying members or sheets taken on the same plane as Figs. 14 and 15.

Referring more particularly to the drawings and especially the forms shown in Figs. 1 to 6 inclusive, the picture or photograph album or folder is shown as comprising a strip or elongated blank 20 of relatively stiff material, such as pasteboard, fibreboard, cardboard, clothboard or other relatively stiff material of any suitable length desired and shown of rectangular form and uniform width with parallel marginal or longitudinal edges 21 and ends 22 and 22a. The strip is divided into a plurality of alternately arranged spaced photograph or picture carrying portions, members, sections or sheets 23 of such lengths and widths to correspond with but slightly wider than the sizes of the photographs, pictures or post cards to be carried thereby or fastened thereto. This is the relatively wide strip and has narrow margins 24 along its opposite longitudinal edges at the sections or portions 23 while the alternate portions therebetween are connected by marginal narrow connections 25 integral therewith or attached thereto and adapted to fold transversely where the ends of the marginal connections 25 join the portions 23 as indicated by the scored lines 26. The marginal connections 25 may be formed by cutting out alternate portions of the strip 20 to form openings 27 within the marginal connections 25 so that the openings are narrower than the strip 20 forming the blank and lie substantially within the margins 24. The narrow strip is indicated at 28 and is less than or corresponds in width to the openings 27 and central sections 23, which is the same as the distance between the margins 24 but like the strip 20 also has its opposite edges 29 parallel as well as the ends 30 and 31 so that the strip or blank forming the same is not only elongated but narrower than the strip 20 but is also of rectangular outline, though this may be varied as desired together with the shape of the foldable portions 23 and the openings 27 of the strip 20. As shown, the strip 28 has alternate rectangular portions 32 and 33 foldable transversely along the scored lines 34. In assembling these strips one end portion of the strip 28, such as the portion 32 is laid across one end of the strip 20 at the portion 23 coextensively and in line but extending in opposite directions so that one end 30 will terminate at the adjacent end of an opening 27 and one end of the strip 20 such as the end 22 will terminate at the inner end of the first section or portion 32 and the corresponding scored or hinged line 34 as shown in Figs. 1, 2 and 3 and the meeting faces fastened together by adhesive as shown at 35 or by clips or other fastening means 36 as shown in Fig. 3 of the drawings. While the adhesive coating 35 is shown applied to one face of each of the rectangular sections 23 and 32 so that the same may be done by machine, this adhesive may be applied when such portions are fastened together and laid one on the other. Across this two ply formation where the ends of the blank strips 20 and 28 are joined together in overlapping relation, a folder 37 may be mounted and fastened in any suitable manner, such as by adhesive or otherwise and as more clearly shown in Figs. 1, 2, 3, 4, 6, and 7 of the drawings in which the front portion 38 may have a window opening 39.

in spaced relation to the edges of which the adhesive or other fastening means may be provided between the front portion 38 and the connected portions 23 and 32 of the strips 20 and 28 so as to accommodate a picture, photograph, snapshot or picture card therebetween, which may be covered by a transparency 40 of Celluloid or other suitable material. This folder is foldable along the lines 41 to provide marginal bindings 42 and flaps 43 and 44 at the back which may simply overlie one another and may be suitably fastened together or connected. They are shown provided with a slot 45 and a tongue 46 to engage therewith and secure the folder in a closed position. However, the use of a folder or cover is optional and may not only be omitted if desired, but any other suitable cover preferably of embossed, tough or highly protective fibre, leather, cardboard or decorative material may be employed containing descriptive matter, advertising relating to the pictures, views within the folder or otherwise as preferred or desired.

Referring back to Figs. 1 to 6 inclusive, it will be noted that the narrow elongated blank forming the strip 28 is substantially the same width as the distance between the marginal portions 24 or slightly less and narrower than the openings 27 between the marginal strips, connections or tapes 25 so as to readily pass through said openings to permit assembling of the device and reverse folding as well as unfolding in exhibiting reversely arranged opposite series of pictures as will be hereinafter more fully brought out.

In the assembling of the album or folder after the opposite end portions 23 and 32 of the blank strips 20 and 28 are anchored together in overlapping relation and extending in opposite directions in line with each other as described as shown in Figs. 1 and 2, the first section or portion 33 is folded on the first line 34 at its juncture with the end of said end portion 32 opposite the end 30, against the portion 32 of the connected portions of the strips and then the next portion 32 which is shown coated with adhesive is folded in the opposite direction against the portion 33 leaving the coated face exposed. The next portion 23 is then folded thereover so that the intermediate marginal connections 25 fold on the scored lines 26 at the juncture of the ends thereof with the overlapped portions 23 and 32 which are fastened together and these marginal connections 25 will straddle or span the portions 32 and 33 outwardly of the marginal longitudinal edges 29 thereof so as to lie along side of the same and contiguously thereto preferably in slightly spaced relation. This will dispose the bottom face of the next portion 23 against the adhesive face of the portion 32 and the margins 24 of the portion 23 will overlie the marginal connections 25 but the adhesive portions lie between said marginal connections 25 and are secured together. However, the portions 23 and 32 instead of being coated with adhesive, glued or pasted together, thus may be otherwise suitably fastened together throughout their surface areas in contact as by means of staples, clips or otherwise. This folding arrangement is repeated throughout the lengths of the strips 20 and 28 and the contacting faces of the portions 23 and 32 fastened together in each instance in the manner more particularly shown in Fig. 4 of the drawings. That is, the portion 33 is folded inwardly on the scored line 34 at its juncture with the overlapped portions of the same and left loose, that is, unconnected or unsecured

thereto, and then the portion 32 is folded outwardly in the opposite direction over the opposite or upper face of the portion 33 and also left free or loose thereof. The marginal connections 25 are then folded inwardly over the margins 24 outwardly of the edges of the strip 28 and folded portions 32 and 33 thereof so that the bottom face of the next portion 23 will contact with the top face of the portion 32 for connecting the same by adhesive, clips or otherwise and this folding is repeated to the ends of the strips. In this connection, it should be noted that the strips may be folded in either direction with the strip 20 uppermost or vice versa, but where adhesive is applied to alternate or spaced portions of the strips, these adhesive surfaces 35 are disposed in opposite directions toward each other, such as with the surfaces 35 of portions 23 disposed downwardly and the corresponding surfaces 35 of the portions 32 disposed upwardly or vice versa, providing the folding arrangement is reversed to the opposite side.

In the use and operation of the album or folder as shown in Figs. 1 to 6 inclusive, with or without the cover as described, when the same is dropped, it will be suspended as shown in Figs. 5 and 6 but when folded will be compact. With the overlapped portions uppermost as shown in Fig. 6, the marginal connections 25 extend or fold downwardly from the bottom of the top portion 23 in front of the margins 24 and connect at the lower ends thereof with the upper end of the next wide portion 23. The narrow portion 33 is loose in front below the overlapped portions and the next portion 32 turns upwardly at the bottom so that the next portion 32 is secured against the bottom face of the adjacent portion 23 and next portion 33 is then folded over the top of the portion 23 at fold line 34 and extends downwardly at the back and free thereof and the next portion 32 is secured to the back face of the next wide portion 23 while the marginal connections 25 of the preceding wide portion 23 extend loosely in back of the next wide portion 23 therebeneath and outwardly of the sides of the narrow portion 32. The lower ends of the preceding wide and narrow portions are unconnected to the portions therebeneath and the marginal connections 25 of the latter wide portion fold down at the front and so on throughout the length of the device. Thus, with a connected wide and narrow portion or section uppermost, the portions in front thereof or on either side are free to drop or swing downwardly in the manner shown in dotted lines 55 in Fig. 5 to expose the two inner faces of the upper sections and pictures, photographs or post-cards mounted thereon by pasting, diagonal corner slits, corner pieces, clips or otherwise as is common in the art to secure pictures or photographs to the sheets or pages of albums or folders. In this way, it is not only possible to exhibit two pictures but two additional pictures or four in all. Until the first member drops in a downwardly swinging cushioned fashion it is not possible for the second one to fall or swing downwardly but as soon as the first one falls or drops, the narrow margins 25 of the hinge connections are transferred from an upwardly extending position to a downwardly extending position and the lower margins 24 are brought into a straight line with the marginal connections 25 so that the hinge is transferred from the top end to the lower end of each picture carrying member or section and this is progressively carried on downwardly so that the loose members alternately

arranged on opposite sides in staggered relation lengthwise of the strips successively and progressively swing down or drop alternately on opposite sides in reverse positions toward the bottom thereby exhibiting the opposite sides together with different photographs or pictures thereon. By folding the upper member downwardly toward one side as shown in Fig. 5, the member in front thereof is left free to drop from the solid line position as shown in said figure as shown on dotted lines and in this way the ones therebeneath alternately on opposite sides will fall by gravity so that whereas an ordinary album will accommodate 12 pictures, a corresponding length of the present structure will accommodate and exhibit 21 pictures which with one on the front of the cover will make 22 pictures in all or substantially twice as many as with the ordinary folder. On the other hand, by folding the upper picture carrying member back to its original position the entire arrangement will be reversed and the alternate carrying members on the opposite sides will be free to drop in alternate opposite staggered relation to the ones which previously dropped thus exhibiting all of the pictures. Owing to the fact that the carrying members progressively and successively drop one at a time from the top to the bottom instead of all at one time, the stresses on the connections are reduced whereas with the old construction the entire weight is placed on the connections since they all drop at the same time or simultaneously instead of intermittently and this prevents tearing or destruction thereof.

In the form of invention shown in Figs. 7 to 17 inclusive, instead of the folder being made of two single sheet strips which of course may be any number of plies, and forming the openings 27 in one strip to produce the portions or sections 23 in spaced relation with correspondingly related openings receiving the narrow portions 32 and 33 of the other strip and the marginal connections 25 forming the tapes or hinged connections between the sections 23, the sections are made up of one or more sheets but shown as two plies 47. There are narrow sections 48 and wide sections 49 each in the form of a rectangular sheet or card independent of the other. One of the carrying members or sections, preferably a wide member is disposed at the top and may be pasted or otherwise secured to the back or inner face of the front portion 38 of the cover 37 so as to firmly anchor the same thereto. Between the plies 47 or along the edges of the sheets, flexible tapes or strips 50 are secured by adhesive or otherwise, and may completely join the sheets together, along the marginal edges thereof. These tapes while preferably inelastic such as ribbon may be gummed or formed of other suitable material and anchored throughout the length of the sections or carrying member or between the plies thereof or only part of the length thereof and are turned downwardly from the top edge as indicated at 51 to form hinged connections at such points. These tapes extend along the marginal edges at the front face of the wide upper carrying member 49 and at their bottom edges connect to the adjacent edge of the next wide carrying member 49 as indicated at 52 and extend lengthwise along the marginal edges thereof between the plies composing the same and to which they are secured by reason of the plies being adhesively secured together or otherwise fastened. This arrangement of the tapes is then repeated throughout the length of the hinged strips formed

by the sections or carrying members. In addition, inner lengthwise or transverse tapes 53 are also secured along the ends or between the plies 47 inwardly of the aforesaid tapes or ribbons in the same manner as previously described but spaced from the opposite longitudinal edges of the wide sections or card carrying members 48. They then extend in parallel relation to form hinged connections between the adjacent ends 5 of the sections or members 48 and 49 as at 54 with the narrow members 48 and are correspondingly fastened between the plies thereof to extend entirely through the same, that is throughout the lengths thereof and in a straight line from the upper wide member. At the lower end of this narrow member the tapes 53 are turned upwardly and back as at 55 to connect with and extend through the narrow section 48 in back which has its upper end connected to the top edge of the wide section 49 therebetween to make exit at the bottom of certain wide sections for connection with the narrow section in front. The lower end of the narrow section in back is connected in a similar manner with and through the wide section therebeneath so that the inner tapes 53 form hinged connections between all of the carrying members and the tapes 50 are alternately connected to the wide members between the plies thereof and loosely span or extend freely along one face of the next wide section therebeneath so as to be alternately turned or bent over from the top at one side of one wide section and from the bottom at the other side of the adjacent wide section with a narrow section therebetween so as to shift the hinged connections merely by folding the cover or the upper picture carrying member the same as in the form previously described so that the carrying members which are loose at the top and which have their hinged connections transferred from the top to the bottom will automatically flop-over and swing downwardly to reverse the positions of the carrying members in alternate opposite staggered relation to exhibit the entire series of pictures arranged on the carrying members the same as previously described. The pictures are designated at 56 in Fig. 13 of the drawings and held in the corner members, slits or clips 57 between or within the widely spaced tapes 50. In this way, when the device is suspended as shown in Figs. 7 and 8 only the alternate free portions of the tapes 50 are exposed in staggered relation or alternately on opposite sides of the folder strip constituted by the hinged or pivotally connected ends of the carrier members or sections thereof. The free tapes on the opposite side are correspondingly arranged except that they are alternately arranged with respect to the others, being bent at the bottom instead of at the top and extending straight at the top instead of at the bottom. Thus, by reversing the position of the cover and the upper carrying member as shown in Fig. 8 of the drawings the opposite alternate carrying members are released to transfer the hinges thereof from the top to the bottom so that they are loose at the top and will drop or swing downwardly as shown in Figs. 9 and 13 of the drawings to exhibit the pictures on the alternate opposite sides of the carrying members whereby they may all be easily and conveniently viewed by the simple manipulation of the cover or top carrying member caused by folding it over and downwardly or upwardly and backwardly in reversed positions in the manner described. Fig. 14 shows the arrangement 70 of the carrying members as illustrated in Fig. 13,

from which it will be noted that in each alternate position there is a single wide carrying member and in alternate positions therebetween, there is an intermediate wide carrying member 49 and narrow carrying members 48 on opposite sides thereof. By reversing the position of the upper carrying member with or without the folder provided thereon and thus also the folder if so provided, the hinged connection of the upper narrow member is transferred from the bottom to the top and is held against the upper wide member as shown in Fig. 15 of the drawings with the alternate carrying members therebetween arranged singly as wide members and the alternate members therebetween wide, with and intermediately of narrow members on each side thereof in staggered or opposite and different relation to the previous arrangement and relation of parts as shown in Fig. 14 of the drawings. By this arrangement, especially with black pasteboard or fibre as commonly used in picture albums and with narrow ribbons or silk tapes, a very high grade product is produced which while slightly more expensive than the previously described form shown in connection with Figs. 1 to 6 inclusive, is very attractive and effectively exhibits snapshots, photographs, picture cards and the like. The cloth or other tapes or ribbons forming the hinged connections between the carrying members are very durable and highly flexible as well as strong and light in weight but particularly unnoticeable as they usually are of black or of a color to correspond with the color of the carrying members. It may also be mentioned that the widely spaced tapes 50 form openings or slots therebetween in spaced or alternate wide members and that the tapes constitute reenforced margins or marginal edges for the alternate wide carrying members or sections 49 and marginal strips or narrow connections therebetween and along the opposite longitudinal edges of the openings produced thereby between which the narrow carrying members may pass the same as in connection with the previously described form where the connections and the carrying members are all cut from one blank or strip. However, the inner tapes as well as the outer tapes are all parallel and form hinged connections between the adjacent meeting ends of alternatively positioned wide and narrow carrying members and between the ends of spaced wide members so that when joined together they form substantially two strips one of which is wider than the other, that is a wide strip and a narrow strip which permits the reversal of the positions of the carrying members in suspended positions once they have been dropped from the cover, merely by reversing the position or folding the cover or upper carrying member over as shown and described not only in the first form but particularly in Figs. 9, 13, 14 and 15 respectively of the present form. Thus, one strip is composed of alternate wide and narrow members hinged together at their adjacent ends and with the wide members alternately connected at their opposite ends by loose marginal strips or tapes overlying the in-between or other alternate ones and said tapes then run through the wide members or are concealed therein between the plies thereof. This form of the invention will also accommodate substantially twice as many pictures or to be exact where the old form would accommodate 12 pictures, the present folder will accommodate 21 pictures which together with the one on the front of the cover makes 22 pictures which are exhibited. While not important it may be men-

tioned that one of the bottom pictures in each instance is exhibited in either folding arrangement.

Attention is also directed to the fact that the tapes or ribbons 50 and 53 where they extend between the two plies of a picture carrying member, sheet or card or extend entirely through the same in concealed form, may terminate at an intermediate point, except where they form marginal connections corresponding to the strips 25 in the first form and are entirely exposed to view along the margins and exposed faces of certain of the carrying members or sections. It should also be noted that the exposed ribbons or marginal connections are alternately exposed or arranged in staggered relation on opposite sides of the exhibiting strip or string of pictures. In Figs. 1 to 6 inclusive and 13, 14 and 15 five or six pictures may be exhibited on each side so that if the picture at the top is number 1 and proceeds downwardly from 1 to 6 inclusive and the picture on the front of the cover is numbered 22, the pictures on the reverse side of those numbered 1 to 6 inclusive may be numbered 18 to 21 inclusive and 17, the latter being at the bottom. When the device is reversed in the manner described and as shown in Figs. 5 and 9 of the drawings, they will be in the position shown in Fig. 15 wherein the exposed top picture is numbered 7 and downwardly from 7 to 12 inclusive while the previously exposed pictures will be hidden from view at the inside the same as were the pictures 7 to 12 inclusive in the position shown in Figs. 13 to 14 of the drawings. The picture 22 will also be exposed at the top and the pictures 13 to 17 inclusive exposed therebeneath with the picture 17 again exposed at the bottom. In Figs. 7 and 8 of the drawings the picture on the front of the cover is indicated at I and there are eight pictures in a row instead of six. These pictures are lettered from J to P inclusive while those on the opposite side are lettered A to H and by reversing the device as shown in Fig. 9 sixteen additional pictures will be exhibited making a total of thirty-one in all as compared with twenty-one or twenty-two in the previous form. Of course, the string or strip of pictures will be made to correspond with the number of picture carrying members or sections, which number may be varied as desired.

It will thus be seen that the device as shown in either form comprises alternate wide and narrow picture carrying sections or members hinged together across their meeting ends, the narrow sections being hinged at each end to the adjacent ends of wide sections and the loose connections extending between corresponding or remote ends of intermediate wide sections alternating with the narrow sections disposed thereagainst. Instead of having alternate portions or faces of strips secured together the ends may be hinged in any known fashion by narrow transverse strips or otherwise so long as they can fold on one another and this may be done by means of transverse strips using Scotch tape or otherwise terminating at the opposite longitudinal edges of the wide and narrow sections instead of intermediate tapes or ribbons spaced from the longitudinal edges thereof and running longitudinally of the sections between the plies thereof or otherwise. Also, the longitudinal tapes along the marginal edges of the wide sections run along said edges to form bindings and instead of being disposed between plies or formed integral with the sections, such longitudinal

marginal portions may be folded over the edges to form bindings and merely fastened together double between opposite ends of the wide sections where they form loose connections or marginal strips forming openings between which the narrow sections pass. In other words the marginal strips or tapes may be formed in any suitable manner separate from the sections and the ends of the alternate narrow and wide sections hinged together in any suitable way to permit them to fold and swing downwardly in the manner shown and described.

While I have illustrated and described the preferred form of construction for carrying my invention into effect, this is capable of variation and modification without departing from the spirit of the invention. I, therefore, do not wish to be limited to the precise details of construction set forth, but desire to avail myself of such variation and modifications as come within the scope of the appended claims.

Having thus described my invention, what I claim as new and desire to secure by Letters Patent is:

1. A picture album of the character described comprising a wide strip consisting of a plurality of contiguous sections with alternate sections solid, and the other alternate sections formed with openings, and a narrow strip also consisting of a plurality of contiguous sections, said strips being arranged with the narrow strip passing through said openings in the wide strip and having spaced apart sections thereof secured to the solid sections on one side of said wide strip, and with the attached sections of said narrow strip being doubled back on unattached sections of said narrow strip.

2. A picture album of the character described comprising a wide strip consisting of a plurality of contiguous rectangular sections hingedly connected together with alternate sections solid, and the other alternate sections formed with rectangular openings, and a narrow strip joined at one end to said wide strip and also consisting

of a plurality of contiguous rectangular sections hingedly connected together, said strips being arranged with the narrow strip passing through said rectangular openings in the wide strip and having spaced apart sections thereof secured to the solid sections on one side of said wide strip, and with the attached sections of said narrow strip doubled back on unattached sections of said narrow strip.

3. A picture album of the character described, comprising a wide strip made up of a plurality of contiguous sections with alternate sections solid and the other alternate sections formed with openings, a hinge connection at each of the opposite edges of each section hingedly connecting that section with the next adjacent sections, and a narrow strip of substantially the same width as said openings joined at one end to said wide strip and also consisting of a plurality of contiguous sections, there being a hinge connection at each of opposite edges of each section hingedly connecting that section with the next adjacent sections, said strips being arranged with said narrow strip passing through said openings in said wide strip and having spaced apart sections secured to the solid sections on one side of said wide strip, and with the attached sections of said narrow strip doubled back on the unattached sections of said narrow strip.

4. A picture album of the character described, comprising a wide strip made up of rectangular solid sections, each of which is joined to the next adjacent solid section by marginal connections defining openings, and a narrow strip joined at one end of said wide strip and consisting of a plurality of contiguous sections, said strips being arranged with the narrow strip passing through said openings in the wide strip and having spaced apart sections secured to said solid sections on one side of said wide strip and with the attached sections of said narrow strip doubled back on unattached sections of said narrow strip.

WLADYSLAV SZYMLEK.
